UNITED STATES PATENT OFFICE.

HENRY J. HANCOCK, OF NEW YORK, N. Y., ASSIGNOR TO GEORGE T. BATCHELOR, OF SOUTH ORANGE, NEW JERSEY, AND SAMUEL STENSON, OF SEACLIFF, NEW YORK.

NEEDLE-FEED CHAIN-STITCH SEWING-MACHINE.

SPECIFICATION forming part of Letters Patent No. 691,311, dated January 14, 1902.

Application filed July 13, 1901. Serial No. 68,218. (No model.)

To all whom it may concern:

Be it known that I, HENRY J. HANCOCK, a citizen of the United States, residing at New York, in the county and State of New York, have invented a new and useful Needle-Feed Chain-Stitch Sewing-Machine, of which the following is a specification.

My present invention is designed as an improvement on the machine covered by the Letters Patent granted to me on the 2d day of July, 1901, No. 677,740; and the object of my present invention is, first, to simplify the construction of the presser-foot; second, to simplify the construction of the guide or fulcrum plate, and, third, to provide a better spring for the presser-foot. I attain these objects by the mechanism illustrated in the accompanying drawings, in which—

Figure 1 is a side elevation of a sewing-machine constructed according to my present invention, a part being broken away. Fig. 2 is a top plan view thereof, and Fig. 3 is a front view of a part of the machine on a larger scale.

In the accompanying drawings like parts are indicated by the same numerals of reference in each of the views, and in the practice of my invention I provide the presser-foot 5 with a perpendicular standard 6, integral with the cross-piece 7, which is pivoted to the frame at 8, and a handle 9 is provided to operate said cross-piece and presser-foot. On the opposite side of the machine an angular extension 10 of the cross-piece 7 is provided, between which and the frame is mounted a compression-spring 11, working on a pin 12 in said extension, and the other end is seated in a socket 13, formed in the side of the frame, as clearly shown in Fig. 3. By reason of this construction it is not necessary to mount a pin or place a stud on the side of the frame to hold the spring in position, and more space is created for the spring, so that a longer and better spring can be used, and the extension will not be prevented coming close to the frame when the presser-foot is raised.

The guide or fulcrum plate 14 is provided with a central longitudinal slot 15, through

which a screw 16 is passed into the cross-piece 50 of the presser-foot, and the metal removed to form said slot is left attached at the lower end thereof and is bent outward at right angles to the plate 14, as shown at 18, and is provided with an eye 19, through which the 55 needle 20 passes, the upper end of the needle being mounted on the crank 21, and the throw of the needle is adjusted by moving the plate 14 up and down on the screw 16, as will be readily understood. The plate 14 is provided 60 with wings 22, which engage the standard 6 of the presser-foot, which acts as a guide for the lower end of said plate. By this construction I get a very cheap and efficient fulcrum-plate, and the adjustment of the same is al- 65 ways in a vertical plane.

By the construction of presser-foot the cross-piece is considerably above the presser-foot, which is curved upward at both ends and makes a very neat and efficient foot. 70

In this class of machines the shaft 23 is rotated, which causes the point of the needle 20 to describe an ellipse and feeds the cloth forward underneath the presser-foot. A hook-needle is used, and the thread is fed to 75 the needle by the spring 24 in a manner described in my other patent. As this spring projects across the path of the needle, the needle would be caught and broken if the shaft were to be rotated backward. To prevent this, I have provided a ratchet-wheel 25, which is mounted on the shaft 23, and I provide a gravity-pawl 26, which is pivoted at 27 to the frame and engages the ratchet-wheel 25, thereby preventing the rotation of 80 the shaft 23 in the wrong direction. By using a gravity-pawl constructed in this manner scarcely any noise is made, which is not the case if a spring-pawl is used, and the pawl can be thrown out of engagement when re- 85 quired.

Having thus described my invention, what I claim as new, and desire to secure by Letters Patent, is—

1. A needle-feed for a chain-stitch sewing- 95 machine, the same comprising a needle, a presser-foot pivoted to the frame of the machine and provided with a vertical standard,

and a plate carried by said presser-foot and serving as a fulcrum for said needle, and provided with wings engaging said standard, as and for the purpose set forth.

5 2. The combination with a chain-stitch sewing-machine of a presser-foot pivoted to the frame of the machine and having an angular extension, the frame of the machine being provided with a socket back of said extension, and a compression-spring mounted in

said socket, and engaging said extension, as and for the purpose set forth.

In testimony whereof I have signed my name to this specification in the presence of two subscribing witnesses.

HENRY J. HANCOCK.
